US00D530624S

(12) United States Design Patent (10) Patent No.: US D530,624 S
Cummings et al. (45) Date of Patent: * Oct. 24, 2006

(54) DISPENSER

(75) Inventors: Bruce Cummings, New York, NY
(US); Nicholas Noe, New York, NY
(US)

(73) Assignee: Colgate-Palmolive Company, New York, NY (US)

() Term: 14 Years

(21) Appl. No.: 29/237,545

(22) Filed: Sep. 1, 2005

(51) LOC (8) Cl. 09-01

(52) U.S. Cl. D9/729

(58) Field of Classification Search D9/723,
D9/726-729, 529, 573, 414, 424; D19/66;
D23/366; D28/4, 7, 9, 44, 44.1, 73, 76; 206/407,
206/438, 527, 823; 221/208, 209, 288-290;
222/173, 465.1, 544, 548

See application file for complete search history.
